UNITED STATES PATENT OFFICE.

DAVID W. R. MORGAN, OF SWARTHMORE, PENNSYLVANIA, ASSIGNOR TO WESTINGHOUSE ELECTRIC & MANUFACTURING COMPANY, A CORPORATION OF PENNSYLVANIA.

CONDENSER.

Application filed March 23, 1927. Serial No. 177,714.

My invention relates to tubular heat exchangers, such, for example, as surface condensers, and the like. In the operation of equipment of this general class, it has been found that smooth flow, such as is usually assumed to take place through all of the tubes, does not, in fact, take place through many of the tubes; and, under operating conditions, it may occur that, in certain tubes, the water stream forms vortices, or more or less flat, or extended spirals, especially for the first two or three feet of the tube.

The tubes in which these irregular conditions of flow prevail may be in any part of the nest, although these conditions are usually the most noticeable in a relatively small area of the nest.

It has been found that the whirling action, or irregular flow of the stream of circulating media is largely responsible for premature failures of the tubes, due to the fact that gaseous media, such as air, or the like, which has become entangled in the stream of circulating media, is caused to impinge against the walls of the tubes, and this attack may be so serious as to cause a failure in a few weeks, or even days.

While conditions, such as these, are most commonly found in installations where circulating media is made up under estuarine or marine conditions, it will be understood that these difficulties may be encountered under various similar conditions.

An object of my invention, therefore, is to provide means for improving the operation of a device of the type described and to preclude, so far as possible, the corrosive action of entrained gases on the tubes and other parts of the circulating system.

Other and further objects of my invention will appear as the description proceeds.

Apparatus embodying the features of my invention is shown in the accompanying drawing, in which:

Fig. 1 is an elevation, partly in section, showing a surface condenser provided with means embodying my invention; and,

Fig. 2 is a sectional elevation of a modified form of apparatus which may be used with the arrangement shown in Fig. 1.

According to my invention, means are provided for de-aerating circulating media at some suitable point before it enters the circulating system of a condenser, or the like.

Such means may be conveniently interposed in the intake conduit for the condenser and may consist of an arrangement for causing the circulating media to cascade in small streams, together with means for removing air and other entrained gases, which may be liberated by the circulating media while in such a finely divided condition. While any suitable air removal apparatus may be used with my invention, means are preferably provided for utilizing the action of circulating media discharged from the condenser as a means for de-aerating that circulating media, which is about to enter the condenser.

In Fig. 1, I show a surface condenser 10, which may be a vertical, double-pass condenser, as shown, or any other tubular heat exchanger. The condenser consists of a shell 11, an inlet water box 12 and a return water box 13. The water box 12 is provided with a connection 14, for admitting circulating media, and with a discharge connection 16. Suitable fluid translating means, such for example, as the circulating pump 17, may be provided. The pump 17 discharges into the intake conduit 18, from whence the circulating media passes into a chamber 19, in which a number of trays 21 are arranged to cause the circulating media to spread out into a relatively thin stream, and to cascade over the various trays to the discharge orifice 22, and through the connection 14 to the inlet water box 12. A suitable connection 23 is provided in the upper portion of the chamber 19, preferably on the top of the chamber 90 as shown, and this connection 23 may lead to any suitable air removal apparatus, as to an air ejector or the like.

Preferably, however, I provide means for removing air from the chamber 19, through the connection 23, by the suction produced by circulating media passing through the discharge conduit 24. In the arrangement shown this means takes the form of a member 26, which is provided with an annular recess 27, and is adapted to fit the periphery of the discharge conduit 24. The member 26 is so arranged as to form an annular chamber with the peripheral surface of the discharge conduit. Suitable openings are provided in the discharge conduit, such as ports 28, which are arranged to provide communication between the annular chamber 27 and

the interior of the discharge conduit and, if desired these ports may be inclined from the outer surface of the discharge conduit downwardly.

5 In the operation of the apparatus thus far described, it will be apparent that media, discharged from the circulating pump 17, will pass through the intake conduit 18, and into the chamber 19, in which the stream of media 10 will be diffused over a wider area, and will pass in relatively thin streams over the various trays 21, and, finally, through the inlet connection 14, to the inlet water box 12. The circulating media then passes through 15 the condenser to the water box 13, from whence it is returned again to the water box 12, and is discharged through the connection 16 to the discharge conduit 24.

20 The action of the circulating media, in passing by the ports 28 in the discharge conduit, is such as to produce suction in the chamber 27. The chamber 27 is, of course, arranged at such a distance, below the level 25 of the connection 23 to the chamber 19, to make available the proper difference in pressure to produce the suction in the chamber 27, which is required to withdraw gaseous media through the connection 23, to the chamber 27, and, through the ports 28, into the 30 discharge conduit.

It will thus be seen that means are provided for liberating entrained gases from 35 circulating media, and for by-passing such gaseous media around the heat exchanger, and for again entraining such gases in the media discharged from the unit.

In Fig. 2, I show a modified form of de-aerating apparatus, which may be used with the arrangement shown in Fig. 1. This 40 apparatus comprises a shell 31, arranged to provide a chamber 32, having an inlet orifice 33, and a discharge orifice 34. A connection, consisting of a flanged, tubular member 36, is inserted through the inlet orifice 33, and 45 extends well into the chamber 32. A tray 37 is provided to receive a fluid passing through the tubular member 36, and the tray is so located, with relation to the member 36, that fluid, discharged from the member 36, fills 50 the tray, and overflows, about the upper periphery of the tray, in a relatively thin stream. After passing over the tray 37, the fluid then passes through the discharge orifice 34, and the connection 14, to the inlet 55 water box 12, and through the condenser, as described in connection with Fig. 1. A suitable air removal connection 38 is arranged to communicate with an upper region of the chamber 32, and if desired, this connection 60 may pass through the upper surface of the shell 31, as shown.

While, with the de-aerating apparatus just described I may use the air removal means shown in Fig. 1, I have shown an air ejector 65 39 which is provided with an entraining

chamber 41, a steam inlet 42 and a diffuser 43.

While I have shown my invention in two forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a power installation, the combination of a surface condenser, an intake conduit and a discharge conduit therefor, means 80 for removing gaseous media from the intake conduit, and means for entraining such gaseous media in fluid passing through the discharge conduit.

2. In a power installation, the combination of a surface condenser, an intake conduit and a discharge conduit therefor, and means for by-passing gaseous media from the intake conduit to the discharge conduit.

3. Means for passing circulating media 90 to a condenser comprising an inlet connection on the condenser, an intake conduit, an enlarged section joining the intake conduit and the inlet connection, one or more trays in said enlarged section and disposed transversely to the direction of fluid flow between said intake conduit and said inlet connection, and means for removing gaseous media from the enlarged section.

4. In a power installation, the combination of a condenser, an inlet connection and an outlet connection for circulating media for the condenser, a chamber having an inlet and arranged to discharge into said inlet connection, one or more trays in said chamber and disposed transversely to the direction of fluid flow to the inlet connection for the condenser, a discharge conduit connected to the discharge connection, said discharge conduit having one or more ports in the 110 walls thereof, and means for connecting said ports with said chamber.

5. In a power installation, the combination of a condenser, an inlet connection and an outlet connection for circulating media for the condenser, a chamber having an inlet and arranged to discharge into said inlet connection, one or more trays in said chamber and disposed transversely to the direction of fluid flow to the inlet connection for the condenser, a discharge conduit connected to the discharge connection, said discharge conduit having one or more ports inclined from the outer surface to the inner surface of said discharge conduit in the direction 125 of fluid flow therethrough, and means for connecting said ports with said chamber.

6. In a power installation, the combination of a condenser, an inlet connection and an outlet connection for circulating media 130

for the condenser, a deaerator arranged to discharge into said inlet connection, a discharge conduit connected to the discharge connection, said discharge conduit being provided with one or more ports in the walls thereof, and means for connecting said ports with said deaerator.

7. In a power installation, the combination of a condenser, an inlet connection and an outlet connection for circulating media for the condenser, a deaerator arranged to discharge into said inlet connection, a discharge conduit connected to the discharge connection, said discharge conduit having one or more ports inclined from the outer surface to the inner surface thereof in the direction of fluid flow therethrough, and means for connecting said ports with said deaerator.
- 20 8. In a power installation, the combination of a condenser, an inlet connection and an outlet connection for circulating media for the condenser, a deaerator arranged to discharge into said inlet connection, and an aspirator for removing gaseous media from the deaerator.

9. In a power installation, the combination of a condenser, an inlet connection and an outlet connection for circulating media for the condenser, a deaerator arranged to discharge into said inlet connection, and means for utilizing the flow of circulating media discharged from the condenser for removing gaseous media from the deaerator.

30 35 10. In a power installation, the combination of a condenser, an inlet connection and an outlet connection for circulating media for the condenser, a deaerator arranged to discharge into said inlet connection, a dis-

charge conduit connected to said discharge connection, a passage from the deaerator to said discharge conduit, and means for utilizing the flow of circulating media through said discharge conduit for drawing gaseous media from the deaerator through said passage and into the stream of media in the discharge conduit.

11. The method of operating a condenser which comprises passing circulating media through the condenser, removing gaseous media from the circulating media before the latter enters the condenser, and entraining such gaseous media in circulating media discharged from the condenser.

12. The method of operating a condenser which comprises translating circulating media to a region above the condenser, continually removing gaseous media from this region, causing the circulating media to cascade in small streams through this region, and utilizing the force of gravity for passing circulating media from this region through the condenser.

13. The method of operating a condenser which comprises translating circulating media to a region above the condenser, utilizing the flow of circulating media from the condenser for removing gaseous media from said region, causing the circulating media to cascade in small streams through said region, and utilizing the potential energy of the circulating media for passing it from said region through the condenser.

In testimony whereof, I have hereunto subscribed my name this eleventh day of March, 1927.

DAVID W. R. MORGAN.
